UNITED STATES PATENT OFFICE.

DAVID W. DORRANCE, OF MINNEAPOLIS, MINNESOTA.

ARTIFICIAL HAND.

Application filed February 5, 1926. Serial No. 86,214.

My invention relates to improvements in artificial hands of the type including a pivoted thumb, an object of the invention being to supply simple, durable and effective 5 means for actuating said thumb.

A further object of the invention resides in providing such thumb actuating means, wherein but little of the mechanism is exposed to view and whereby a "follow-up" 10 grip of the thumb is effected.

Another object of the invention is to supply a thumb actuating means, as above, the same being adapted constantly to resist opening swinging movement of the thumb 15 by extraneous forces.

With the foregoing and other objects in view, which will appear in the following description, the invention resides in the novel combination and arrangement of parts 20 and in the details of construction herein-after described and claimed.

In the drawings, Fig. 1 is a side view of an artificial hand embodying my invention, the detachable side plate being removed to 25 disclose the interior mechanism which otherwise would be concealed. Fig. 2 is a view similar to Fig. 1, the thumb being illustrated as swung back out of the normal position shown in Fig. 1 and the associated parts 30 shown in the relation assumed thereby in such position of said thumb; Figs. 3 and 4 are transverse sectional views respectively taken on the lines 3—3 and 4—4 of Fig. 1, and Fig. 5 is a perspective view in detail of the traveler which is reciprocably disposed within the hand proper.

Reference being had to the drawings, it will be observed that the illustrated embodiment of my invention includes a structure 40 closely simulating the human hand, said structure including a metacarpus or main hand portion 10, fingers 11 and a thumb 12. Preferably, the main hand portion 10 and fingers 11 are built up and carved out of 45 a light, strong wood. The thumb 12 is formed independently of said parts 10 and 11 of the hand, said thumb being pivoted to the hand proper by means of a pin 13, a portion 14 of said thumb on which a cam 50 surface 15 is formed, finding room to swing in a recess 16 cut into the main hand portion 10 and opening laterally at the front thereof. A second recess 17 also opening at the front of the hand is formed in said hand portion 55 10 and joining said recesses 16 and 17 is a way 18 extending longitudinally of the hand. Thumb actuating parts, presently to be described, are housed within the recesses 16 and 17 and way 18, all being normally covered by means of a side plate 10^a constituting a part of the hand proper, and removably secured in place by screws 19 threaded into the body of the main hand portion 10. Reciprocably slideable in the way 18 is a traveler 20 (Fig. 5) which has 60 a head 21 providing a cam 22, said head being notched to provide a spring seat 23. Opposite the head 21, the traveler body 20 is notched, as at 24, to form an abutment 25. The head 21 of said traveler 20 occupies positions within the recess 16, while the abutment 25 occupies positions within the recess 17. Interposed between the wall 26 of the recess 16 and the seat 23 in the traveler 20 is a coiled expansion spring 27, which 65 yieldingly operates to push the traveler 20 back in the way 18. Such backward movement of said traveler 20 is attended with a closing swinging movement of the thumb 12 due to the form of the cam 22 and the 70 cam surface 15 on the thumb with which said cam coacts. In this connection it is important to note that the spring 27, operating through the follower 20, effects a "follow-up" grip of the thumb against an 75 object tending to become free from the hold of said thumb. Further, it will be noted that any tendency of the thumb to open, as by an external force, will be effectively resisted by the follower 20, due to the design 80 of the cam 22 and cam surface 15, whereby any pressure of the latter against the cam 22 results mainly in pressing the follower 20 against the wall 28 of the recess 16. A lever 29, playing in the recess 17, is pivoted 85 medially to the main hand portion 10 on a screw 30 applied thereto. The inner end of this lever presents a curved edge 31 to the abutment 25 on the follower 20, the outer end of said lever being formed with an eye 100 32 in which the end of a pull-cord 33 is caught. From the foregoing it will be understood that, when the pull-cord 33 is slackened, the spring 27 will force the follower 20 back with the result that the thumb 105 12 is swung closed against an object between said thumb and the first fingers 11 or against said fingers (Fig. 1) in the absence of such object. It will also be understood that a pull upon the cord 33 will swing the lever 110 in a direction to thrust the traveler 20 forward against the action of the spring 27.

During such movement of said traveler 20, the thumb 12 is allowed to swing open and to so swing said thumb, I provide a link 34, the same being pivoted at one end on a screw 35 in the lever 29 and at its other end on a screw 36 in the thumb portion 14. This link, plays in a groove 37 in the inner side of the side plate 10^a and may be relatively light as its sole function is to swing the 10 thumb 12 open as it is permitted so to swing by the forwardly moving traveler 20. And it is, of course, understood that there is practically no resistance against the opening of the thumb 12 as compared with the resistance 15 encountered against the closing thereof and met by the relatively strong structure including the spring pressed traveler 20.

At the end of the main hand portion 10, opposite the fingers 11, is a threaded stud 20 38 for application to the usual arm-stump socket. With this stud screwed into such socket and the cord 33 appropriately pulled and slackened, my improvement provides an effective substitute for the human hand that 25 is slightly in appearance and easy to use.

Changes in the specific form of my invention, as herein disclosed, may be made within the scope of what is claimed without departing from the spirit of my invention.

Having described my invention, what I 30 claim as new and desire to protect by Letters Patent is:

1. An artificial hand including a main portion provided with fingers and with a 35 thumb pivoted thereon and formed with a cam surface, a traveler reciprocably mounted within said main portion and formed with a cam thereon adapted to coact with said cam surface to resist opening swinging movement of said thumb by extraneous force, also to impart closing swinging movement to the thumb upon movement of the 40 traveler in one direction, an expansion spring operating against said traveler to move the same in that direction, and an actuating lever pivoted on said main portion, one end of said lever co-operating with 45 said traveler to shift the same against the action of said spring and thereby free the 50 traveler from the thumb.

2. An artificial hand including a main portion provided with fingers and with a thumb pivoted thereon and formed with a

cam surface, a traveler reciprocably mounted within said main portion and formed with a cam thereon adapted to coact with said cam surface to resist opening swinging movement of said thumb by extraneous force, also to impart closing swinging movement to the thumb upon movement of the 55 traveler in one direction, an expansion spring operating against said traveler to move the same in that direction, and an actuating lever pivoted on said main portion, one end of said lever co-operating with 60 said traveler to shift the same against the action of said spring and thereby free the traveler from the thumb, and a link joining said lever with said thumb for imparting opening swinging movement to the latter. 70

3. An artificial hand including a main portion provided with fingers and with a thumb pivoted thereon and formed with a cam surface, a traveler movably mounted within said main portion and formed with a cam thereon adapted to coact with said cam surface to resist opening swinging movement of said thumb by extraneous force, also to impart closing swinging movement to the thumb upon movement of the 75 traveler in one direction, means for moving said traveler in that direction, other means for moving the traveler in the opposite direction to free the thumb, and additional means associated with said last mentioned 80 means for imparting opening swinging movement to the thumb.

4. An artificial hand including a main portion provided with fingers and with a thumb pivoted thereon and formed with a cam surface, a traveler reciprocably mounted within said main portion and formed with a cam surface thereon adapted to coact with said first cam surface to resist substantially uniformly the opening swinging movement of the thumb by extraneous force in the various relative positions of said cam surfaces, also to swing the thumb toward the fingers upon movement of the traveler in one direction, means for moving the traveler in that direction, and independent means for oppositely moving said traveler. 95

In testimony whereof, I have signed my name to this specification.

DAVID W. DORRANCE.
